UNITED STATES PATENT OFFICE

153,204

DESIGN FOR A NECKLACE OR THE LIKE

Herman Bogoff, Chicago, Ill.

Application December 6, 1947, Serial No. 142,984

Term of patent 3½ years

(Cl. D45—16)

To all whom it may concern:

Be it known that I, Herman Bogoff, a citizen of the United States, residing in Chicago, in the county of Cook and State of Illinois, have invented a new, original, and ornamental Design for a Necklace or the like, of which the following is a specification, reference being had to the accompanying drawing, forming part thereof.

Fig. 1 is a front elevational view of a necklace or the like, showing my design;

Fig. 2 is the side view thereof; and

Fig. 3 is an enlarged view of a fragmentary section of the necklace chain as shown in Fig. 1.

I claim:

The ornamental design for a necklace or the like, substantially as shown.

HERMAN BOGOFF.
